UNITED STATES PATENT OFFICE.

ARTHUR WRIGHT, OF NEW YORK, N. Y.

SAFETY-PIN.

1,214,638.

Specification of Letters Patent.

Patented Feb. 6, 1917.

Application filed March 23, 1912. Serial No. 685,649.

To all whom it may concern:

Be it known that I, ARTHUR WRIGHT, of New York, in the county of New York and in the State of New York, have invented a certain new and useful Improvement in Safety-Pins, and do hereby declare that the following is a full, clear, and exact description thereof.

My invention relates particularly to safety pins which are so constructed as to be provided with a head to engage and protect the point of the pin.

The familiar type of safety pin which is in general use is so constructed that the pin may be closed by grasping the pointed end of the sharpened prong with one finger and the head which is attached to the other prong by means of the other finger. The end of the pointed prong may in this manner be inserted in the head on either side thereof. In order to release the pointed prong from the head, it is necessary to insert the finger beneath the head and push the goods back, away from the head until the finger underlies the sharpened prong between the head and the goods which is carried by the sharpened prong. A finger being now applied to the other prong, a pressure on the sharpened prong will elevate the sharpened prong so as to cause it to be released from the head. This operation of opening the safety pin is often very painful, inasmuch as the goods are very often tightly gathered on the pointed prong, and as a considerable amount of force is required to push the goods back away from the head which engages the pointed prong. Furthermore, in inserting the finger below the head to push the goods back, it is necessary to insert the finger in a very small and awkward space which adds to the discomfort. Again, when the releasing operation is being effected by pressing the sharpened prong upwardly so as to release it from the head, it frequently happens that the finger becomes wounded by the sharpened end of the prong. A further disadvantage of this type of pin lies in the fact that the sharpened prong may be at any time released from the head by a slight pressure merely reversing the operation which is carried out in closing the pin.

The object of my invention is to provide a safety pin which is so constructed that the safety pin may be readily opened by operating the pin from the upper part, that is to

say, the part or prong which does not engage with the goods, and without any danger of injury to the fingers. Another object of my invention is to provide a safety pin which is so constructed that when the pointed end of the pin engages with the head, the pointed end is effectively locked in position so as to prevent an accidental or unintended release of the pointed end from the head.

Still a further object of my invention is to provide a safety pin operating in the manner described, but which is so arranged that the operations above referred to can be carried out without the necessity of resetting any of the parts prior to engagement of the head with the pointed prong. Furthermore, by means of my invention, I avoid all of the disadvantages above referred to as being present in the safety pin of the usual type.

My present invention constitutes an improvement upon the invention set forth in my patent upon a safety pin, No. 1,019,578, granted March 5th, 1912.

Although my invention is capable of embodiment in many different forms, for the purpose of illustration I have shown it as embodied in two different modifications, and as illustrating the same—Figure 1 is a side elevation of one modification of my invention showing the safety pin in its closed position; Fig. 2 is a side elevation of the same showing the parts in the position in which the pointed end of the prong has just been released from the head; Fig. 3 is a similar view of the same showing the position of the parts when the head has been automatically reset; Fig. 4 is a vertical section of the head used in the modification already described, taken on line 4—4 of Fig. 5; Fig. 5 is a vertical transverse cross-section of the same modification; Fig. 6 is a side elevation of another modification of my invention showing the pointed prong released from the head; Fig. 7 is a horizontal section taken on line 7—7 of Fig. 6; and Fig. 8 is a side elevation of the end of the prong.

In Figs. 1 to 5, I have provided a bent wire 1 having a coil 2 in the middle thereof, on one side of which there is a sharpened prong 3 and on the other side of which there is a bent prong 4 which engages with a head 5. The bent prong 4 has at its extreme end a downwardly directed portion 6 and an upwardly bent portion 7, the upwardly bent portion 7 being substantially

parallel, though not necessarily so, with the downwardly bent portion 6, the upwardly bent portion 7 ending in a backwardly bent portion 8 which is substantially parallel 5 with the main body of the prong 4. The prong 4 carries a coiled spring 9, one end of which rests in the slot between the downwardly and upwardly bent portions 6 and 7 of the prong, while the other end of the 10 spring rests against a concave washer 10, fitting over the prong 4.

The head of the pin comprises a barrel portion 11 and a shield portion 12, the latter being designed to receive the pointed 15 end of the prong 3 and being provided at each side with an angularly shaped, inwardly directed tongue 13 which prevents the removal of the pin and prevents the accidental movement of the pointed end of 20 the prong 3 from said shield. The barrel portion 11 of the head 5 is constructed at its lower end and at either side with a transversely directed flange 14 extending from one end of the barrel portion to the other, 25 and being inclined upwardly as shown in Fig. 4. The upper end 15 of the upper flange 14 acts as a stop or abutment co-operating with the upwardly directed bent portion 7 of the prong 4 in the closed position 30 of the pin, the portion of the prong 4 which lies between the upwardly and backwardly bent portions 7 and 8 lying directly against the abutment 15. At the wider end of the barrel, said barrel is provided with 35 a second abutment in the form of an inwardly directed flange 16 surrounding the same, the purpose of which is to receive the convex face of the washer 10 and thereby control the movement of the spring 9. It 40 will be noted that the end of the barrel 11 which carries the flange 16 is inclined rearwardly, that is to say, at an angle to the upper edge of the barrel portion of the head, for a purpose which will be described 45 hereinafter. The shield portion 12 may have at either side thereof an inwardly and downwardly directed tongue 13 to lock the pointed prong in position.

In the operation of the safety pin, in the 50 closed position of the pin the parts are located in the position shown in Fig. 1, with the upwardly and backwardly bent portions 7 and 8 engaging with the stop or abutment 15 in the barrel of the head 5, and with the 55 main body of the prong 4 resting against the upper edge of the interior of the barrel portion 11. In this position, that is to say, the closed position of the pin, the pointed prong 3 cannot be accidentally released by 60 a movement upwardly and over the edge of the shield 12, because of the presence of the tongues 13, one of which is situated at either side of the pin. The pointed prong is, consequently, locked in position once that the 65 pin has been closed. In order to open the

pin it is merely necessary to grasp the head between the thumb and forefinger and move the inner end thereof upwardly in the direction of the arrow shown in Fig. 1. The movement of the head in this direction releases the upwardly bent portion 7 from engagement with the stop or abutment 15 and when so released the head 5 may be pulled longitudinally away from the wire portion of the pin in opposition to the force of the 70 spring 9 until the pointed end of the prong 3 is released from the shield 12. The position of the parts when the pin has been released in this manner is shown in Fig. 2. Upon releasing the grasp upon the head, 80 the spring 9 will immediately move the head back into its initial position by first moving the bent portion 7 to the end of the barrel portion 11 over the stop or abutment 15, and by finally moving the prong 85 4 upwardly until it rests against the upper edge of the barrel 11. The latter portion of the movement is effected by reason of the inclined position of the flange 16, inasmuch as it will be seen that the spring is in a 90 more extended position when the prong 4 is adjacent to the upper edge of the barrel portion 11 than when below the same. When the head has been thus reset, the parts are in the position shown in Fig. 3, and in 95 order to close the pin it is now merely necessary to insert the pointed end of the prong 3 over either side of the shield 12.

In Figs. 6 to 8, I have shown another modification of my invention in which the 100 spring and the washer for limiting the movement of the same are omitted, and in which there are only two parts to the pin, that is to say, a head 17 and a bent wire 18 having a coil 19 in the middle thereof, 105 said bent wire being provided with a sharpened prong 20, and at the other side of the coil with a prong 21 for engaging the head. The prong 21 has at its end a downwardly bent portion 22, an upwardly bent portion 110 23, and a rearwardly and laterally bent portion 24. The head 17 comprises a shield 25 and a barrel portion 27. The barrel portion 27 has at each side thereof an inwardly directed flange 28, said flanges 28 being inclined upwardly as shown in the drawings. The upper end of the upper flange 28 constitutes a stop or abutment for the upwardly bent portion 23 of the prong 21. The larger end of the barrel portion 27 has at one side 115 thereof a flange 29 to act as a stop for engagement with the laterally bent portion 24. This modification of my invention operates in the same manner as the modification previously described, except that after 120 the release of the head from the sharpened prong 20 it is necessary to reset the head upon the prong 21 before the pin is closed, and except that the longitudinal movement of the head on the prong 21 is limited by 125 130

the laterally bent portion 24 instead of being limited by the presence of the spring and washer previously described.

While I have described my invention above in detail it is to be understood that many changes may be made therein without departing from the spirit of my invention as set forth in the claims.

I claim:

10 1. In a safety pin, a head having an abutment, a sharpened prong, a second prong connected thereto and having an offset portion engaging with the abutment in the plane of the prongs and releasable from engagement therewith to release the sharpened prong by a movement of the prongs in said plane, said abutment being located between the two prongs.

20 2. In a safety pin, a head having an abutment in the interior of the head, between the two sides thereof, a sharpened prong, a second prong connected thereto and having an offset portion engaging with the abutment in the plane of the prongs and releasable from engagement therewith to release the sharpened prong by a movement of the prongs in said plane.

30 3. In a safety pin, a head having an abutment in the interior of the head, a sharpened prong, a second prong connected thereto and having an offset portion engaging with the abutment in the plane of the prongs and releasable therefrom to release the sharpened prong by a movement of the prongs in said plane, said abutment being located between the two prongs.

40 4. In a safety pin, a head having an abutment in the interior of the head between the two sides thereof, a sharpened prong, a second prong connected thereto and having an offset portion engaging with the abutment in the plane of the prongs and releasable from engagement therewith to release the sharpened prong by a movement of the prongs in said plane, and said head having a second abutment preventing the separation of the prong from the head.

50 5. In a safety pin, a head having an abutment in the interior of the head, a sharpened prong, a second prong connected thereto and having an offset portion engaging with the abutment in the plane of the prongs and releasable therefrom to release the sharpened prong by a movement of the prongs in said plane, said abutment being located between the two prongs, and said head having a second abutment preventing the separation of the prong from the head.

60 6. In a safety pin, a head having an abutment, a sharpened prong, a second prong connected thereto and engaging with said abutment, to normally prevent longitudinal movement of the prongs with regard to the head so as to prevent the release of the sharpened prong from the head, said head

being movable longitudinally of the prongs to release the sharpened prong from the head and means for returning the head to its original position when the sharpened prong has been released by said movement. 70

7. In a safety pin, a head having an abutment, a sharpened prong, a second prong connected thereto and engaging with said abutment, to normally prevent longitudinal movement of the prongs with regard to the head so as to prevent the release of the sharpened prong from the head, said head being movable longitudinally of the prongs to release the sharpened prong from the head and means for returning the head to 80 its original position when the sharpened prong has been released by said movement, comprising a spring.

8. In a safety pin, a head having an abutment, a sharpened prong, a second prong connected thereto and engaging with said abutment, to normally prevent longitudinal movement of the prongs with regard to the head so as to prevent the release of the sharpened prong from the head, said head 90 being movable longitudinally of the prongs to release the sharpened prong from the head and means for returning the head to its original position when the sharpened prong has been released by said movement, 95 comprising a spring surrounding said second prong.

9. In a safety pin, a head having an abutment, a sharpened prong, a second prong connected thereto and engaging with said 100 abutment, to normally prevent longitudinal movement of the prongs with regard to the head so as to prevent the release of the sharpened prong from the head, said head being movable longitudinally of the prongs 105 to release the sharpened prong from the head and means for returning the head to its original position when the sharpened prong has been released by said movement, comprising a spring surrounding said second 110 prong, said second prong having a stop to limit the movement of the spring in one direction.

10. In a safety pin, a head having an abutment, a sharpened prong, a second 115 prong connected thereto and engaging with said abutment to normally prevent longitudinal movement of the prongs with regard to the head so as to prevent the release of the sharpened prong from the head, said 120 head being movable longitudinally of the prongs to release the sharpened prong from the head, means for returning the head to its original position when the sharpened prong has been released by said movement, comprising a spring surrounding 125 said second prong, said second prong having a stop to limit the movement of the spring in one direction, and a washer for limiting its movement in the other direction. 130

11. In a safety pin, a head having an abutment near one end and a second abutment near the other, a sharpened prong, a second prong connected thereto and engaging with said abutment, to normally prevent longitudinal movement of the prongs with regard to the head so as to prevent the release of the sharpened prong from the head, said head being movable longitudinally of the prongs to release the sharpened prong from the head, means for returning the head to its original position when the sharpened prong has been released by said movement, comprising a spring surrounding said second prong, said second prong having a stop to limit the movement of the spring in one direction, and a washer for limiting its movement in the other direction, said washer engaging with said second abutment. 50
- 10 15 20
12. In a safety pin, a head having an abutment near one end and a flange-abutment near the other, a sharpened prong, a second prong connected thereto and being located in engagement with said abutment, to normally prevent longitudinal movement of the prongs with regard to the head so as to prevent the release of the sharpened prong from the head, said head being movable longitudinally of the prongs to release the sharpened prong from the head, means for returning the head to its original position when the sharpened prong has been released by said movement, comprising a spring surrounding said second prong, said second prong having a stop to limit the movement of the spring in one direction, and a washer for limiting its movement in the other direction, said washer engaging with said flange-abutment, and adapted to slide over the same when the second prong is being released from the other abutment. 55
- 25 30 35 40
13. In a safety pin, a head having an abutment near one end and an inclined flange-abutment near the other, a sharpened prong, a second prong connected thereto and engaging with said abutment, to normally prevent longitudinal movement of the prongs with regard to the head so as to prevent the release of the sharpened prong from the head, said head being movable longitudinally of the prongs to release the sharpened prong from the head, means for returning the head to its original position when the sharpened prong has been released by said movement, comprising a spring surrounding said second prong, said second prong having a stop to limit the movement of the spring in one direction, and a washer for limiting its movement in the other direction, said washer engaging with said inclined flange-abutment, and adapted to slide over the same when the second prong is being released from the other abutment. 60
- 45
14. In a safety pin, a head having an abutment in the interior of the head between the two sides thereof, a sharpened prong, a second prong connected thereto and having an offset portion engaging with the abutment in the plane of the prongs and releasable therefrom by a movement of the prongs in said plane, said abutment being located between the two prongs and said head having a second abutment preventing the separation of the prong upon the head. 65
- 70
15. In a safety pin, a head having an abutment in the interior of the head between the two sides thereof, a sharpened prong, a second prong connected thereto and having an offset portion engaging with the abutment in the plane of the prongs and releasable from engagement therewith by a movement of the prongs in said plane, said abutment being located between the two prongs and said head having at its rear edge a second abutment preventing the separation of the prong from the head. 75
- 80
16. In testimony that I claim the foregoing I have hereunto set my hand. 85

ARTHUR WRIGHT.
